LIQUID SPRAYING DEVICE

Henry L. Friedman, East Cleveland, and Max Pollock, Cleveland, Ohio; said Pollock assignor to William J. Wesseler, East Cleveland, Ohio

Application March 4, 1935, Serial No. 9,182

7 Claims. (Cl. 299—56)

This invention, as indicated, relates to a liquid spraying device. More particularly, it comprises a structure providing means for spraying liquid over extended areas especially where water pressures are low and where other types of devices cannot be used effectively.

The principal object of the present invention is to provide a structure of few parts and simple and economical to manufacture and assemble, 10 and of large area of effectiveness.

Another object of the invention is to combine with a structure providing hydraulic pressure below a plurality of orifices together with air pressure, means for maintaining and supplementing 15 the normal hydraulic pressure of the device.

A further object of the invention is to provide a combined air pressure and hydraulic pressure device wherein the liquid in a reservoir rises to a point substantially above the point of discharge of the fluid, and in addition may be subjected to the action of an air cushion to control 20 the flow of liquid.

Another object of the invention is to introduce 25 a jet controlling effect which will increase the range of action of the device.

Other and further objects of the invention will appear in the course of the following description.

To the accomplishment of the foregoing and related ends, said invention, then, consists of 30 the means hereinafter fully described and particularly pointed out in the claims, the annexed drawing and the following description setting forth in detail certain structures embodying the invention, such disclosed means constituting, 35 however, but several of various forms in which the principle of the invention may be used.

In said annexed drawing:

Figure 1 is a central vertical sectional view of one type of structure embodying the principles 40 of the invention;

Figure 2 is a top plan view of the structure shown in Figure 1;

Figure 3 is a view similar to Figure 1, showing a modified form of construction;

Figure 4 is a top plan view of a multiple unit device with the units substantially similar to those shown in Figure 1;

Figure 5 is a front elevation partly in section, with the sections taken along the line 5—5, 50 shown in Figure 4;

Figures 6, 7 and 8 are each central vertical sectional views illustrating different modified forms of construction embodying the principles of the invention;

Figure 9 is a central vertical section of a modi-

fied form of multiple unit embodying the principles of the invention;

Figure 10 is a perspective view, cut away in part, showing the pulsating vane mechanism; and

Figure 11 is a fragmentary detail view showing the speed regulating device for the pulsating vane.

The invention as illustrated in the drawing may embody a number of different forms, all 10 acting under one general principle, but having different structural characteristics and producing somewhat different effects in use.

As shown more particularly in Figures 1 and 2, one type of construction embodying the principles of the invention may comprise a casing of substantially semi-spherical shape, the casing being formed of a circular base 1 having a marginal flange 2 extending upwardly, and having a semi-spherical top member 3 engaged with in said flange and secured thereto in liquid-tight relation. Centrally of the under side of the upper member a cylindrical member 4 is provided, the upper end of said member being secured by soldering or the like to the upper inner wall of 25 the upper member, and the open lower end 5 being spaced a slight distance from the base member. The cylindrical member 4 is thus adapted to provide an air cushioning chamber when the remainder of the casing is filled with 30 liquid.

The liquid supply is provided through an inlet terminal 6 secured to the upper member adjacent the base member of the casing. A screw-threaded coupling member 7 of conventional 35 form is supported upon the outer end of the inlet member in order to permit the attachment of a garden hose or like device to the structure at such point.

The semi-spherical upper member 3 is preferably provided with very small perforations 8, preferably distributed along radial lines about the circumference of the upper member except adjacent its central and lower portions which are free of perforations.

The device shown in Figures 1 and 2 when connected with a liquid supply having low pressure will have a large radius of action for the jets emerging through the apertures 8 for the reason that such apertures collectively are of substantially less area than the aperture of the inlet member 6 and thus the full liquid pressure of the line will be imposed upon each of the jets issuing through the small perforations. The cylindrical member 4 will serve to capture air 50

55

within its upper portion 9 when the casing is filled and this air cushion will serve to maintain substantial uniformity of the jets even though there may be minor fluctuations from time to time in the pressure of the supply line.

In the form of construction shown in Figure 3, all the parts are similar to those shown in Figures 1 and 2, with the exception of the member providing the air chamber, which, in the form shown in Figure 3, is not a cylindrical member but an integrally formed inverted cup-shaped member 11 having a base member 12 conforming to the contour of the semi-spherical upper wall of the chamber, and having its side walls 13 tapering downwardly and inwardly to an open neck portion 14 of less width than the width of the bottom of said chamber. The member 11 may be readily attached to the under face of the upper member of the casing by soldering or sweating the same into secure engagement, and due to its shape will retain the air cushioning in operative relation to the fluid even though the member is somewhat inclined from its normal position.

The structure shown in Figures 4 and 5 provides for multiple discharge units 15, 16 and 17, each substantially of the shape shown in Figure 1, but having a somewhat different distribution of the discharge apertures 18 on the upper member, which cover three fourths of the central circumferential area of the end members 15 and 17 and cover opposite lateral quadrants of the central member 16. The central member 16 is provided with lateral couplings 21, 22, respectively, which are connected by means of short sections 30 of hose or pipe 23, 24, with the couplings 25, 26 35 of the respective end members. The main water supply is received through the coupling 27 on the central member which is connected with the garden hose or other source of liquid to be distributed.

Under certain conditions it may be desirable to provide an air chamber on the fluid reservoir in an elevated position in the manner shown in Figures 6 to 9, inclusive, such air chambers being adapted to contain liquid at a level somewhat 45 above the level of the discharge apertures of the device and having an air cushioning member above the elevated liquid column. Each of the forms illustrated embodies a somewhat different structural combination.

The device shown in Figure 6 comprises a casing of substantially the shape of that shown in Figure 1, having a base plate 31, an upper semi-spherical member 32 provided with apertures 33 around its mid-circumferential area, and provided centrally with a screw-threaded opening 34 with 50 in which is engaged the screw-threaded shank 35 of a tubular member open at its lower end 36 and having an enlarged bulb shaped closed upper end 60 to provide an air chamber. A lock nut 38 serves to hold the adjustable air cushioning member in any predetermined position of adjustment. The liquid supply is received through a tube 41 having an upwardly turned inner end 42 engaged centrally in alignment with the adjustable air cushion member and preferably entering the same to a slight degree. The liquid supply may be directly connected with the inlet tube 41 or said tube may have interposed between its liquid supply connection 43 and its discharge end, a device 65 for creating pulsating effects in the liquid supply stream.

The device for creating such pulsating effects may take various forms, but the structure shown in Figures 10 and 11 will serve to momentarily

obstruct the free flow of liquid through the inlet passageway and thereafter open to a position of full flow and subsequently again reduce the flow, so that intermittent pressure effects will be obtained. The device in detail comprises a casing 5 54 provided at one end with a coupling member 45 and at its opposite end with a connection with the inlet tube 41. A substantially Y-shaped vane 47 is provided within the casing which is of rectangular cross-section. The Y-shaped member has a transverse pivot member 48 at a central position and such pivot member passes through a packing gland 49 and terminates in a disk 51 on the upper side of the casing. A retarding device in the form of a spring finger 52 is secured at its 10 opposite end 53 to the upper side of the casing and is provided with a tension adjusting member 54 having its shank extending through an aperture in said spring and having a screw-threaded lower end 55 engaged in a screw-threaded recess 56 in the upper casing wall, whereby any desired tension may be placed upon the spring finger, thus creating a predetermined amount of friction upon the terminal 51 of the pivot member of the movable vane. 15 20 25

In the construction shown in Figure 7, the chamber is substantially of the shape shown in Figure 1, but the air chamber device is formed by means of a cylindrical section of pipe 61, having a screw-threaded central portion 62 engaged through a central aperture 63 in the upper casing member 64. The pipe 61 is closed at its upper end by means of a cap 65 screw-threadedly engaged thereover. The device differs from that shown in Figure 1 in that the air cushion is supported 30 above a column of liquid at a higher level than the level of the discharge aperture through the casing. 35

The structure shown in Figure 8 is likewise similar to that shown in Figure 1, the upper casing member 71 being formed with an upwardly projecting socket 72 within which is securely engaged a cylindrical member 73 which projects downwardly toward the base member, its open lower end 74 being spaced therefrom any desired 40 45 distance. The cylindrical member 73 may be screw-threadedly engaged within the central section 72 of the upper member or may be soldered or sweated into permanently secured position within the same. 50

In the form of construction shown in Figure 9, a series of units having substantially the structural characteristics of the device shown in Figure 6, is provided. In such device a single elongated conduit 81 is provided, connected at one 55 end 82 with a source of fluid supply and having a series of upstanding discharge members 83 positioned centrally beneath inverted bulb shaped air cushioning members 84 which are engaged through apertures 85 centrally of the walls of the 60 upper members 86 of the respective casings. The air cushioning members may be adjustable in the manner shown in Figure 6 or may be permanently secured in predetermined relation to the casing as shown in Figure 9. The discharge perforations are preferably positioned in the manner similar to those shown in Figure 4, and the total collective area of the discharge perforations is of less extent than the area of the inlet connection. If desired, a pulsating member such as shown in 65 Figures 10 and 11 may be applied to the free end 70 75 of the conduit in advance of its connection to the source of liquid supply.

The different forms of structure shown are intended to be merely illustrative and not exhaust-

tive of all the forms of such devices which may be provided within the scope of the claims of the application. The device, when used as a lawn sprinkler, will exhibit a wide range of coverage and the flow will be maintained substantially uniform owing to the air cushioning effect of the air chamber within the device. Where, however, the supply line is provided with a device to cause pulsating or intermittent flow of fluid into the pressure chamber, the discharge of the device will be a pulsating effect and will have a very wide range of action during the maximum pressure conditions developed by the hydraulic ram effect induced through the intermittent flow.

15 Other modes of applying the principle of our invention may be employed instead of those explained, change being made as regards the structure herein disclosed, provided the means stated by any of the following claims or the 20 equivalent of such stated means be employed.

We therefore particularly point out and distinctly claim as our invention:

1. An apparatus of the character described having in combination, a substantially closed 25 chamber having an inlet passageway connected with a source of liquid under pressure and having a series of discharge orifices in at least one wall thereof, the orifices being of less area collectively than the area of the inlet passageway, and a 30 vertically positioned tube having a closed top and an open lower end in spaced relation to the bottom of said chamber and providing air cushioning means for the liquid within the chamber located substantially centrally of said chamber.

35 2. An apparatus of the character described having in combination, a substantially closed chamber having a flat bottom and an upper area of substantially semi-spherical contour, an elongated hollow member open at its lower end and closed at its upper end and engaged in liquid-tight relation through the upper portion of said chamber and having its open lower end in spaced relation to the bottom of said chamber, an inlet opening adjacent the lower portion of said chamber, and a plurality of discharge orifices in the 40 upper portion of said chamber, said orifices being collectively of less area than the area of the inlet opening.

3. An apparatus of the character described having in combination, a substantially closed chamber having a flat bottom and an upper area of substantially semi-spherical contour, an elongated hollow member open at its lower end and closed at its upper end and engaged vertically in liquid-tight relation through the upper portion of said chamber and having its open lower end in spaced relation to the bottom of said chamber, means for adjusting the vertical position of said hollow member, an inlet opening adjacent the lower portion of said chamber, and a plurality of discharge orifices in the upper portion of said chamber, said orifices being collectively of less area than the area of the inlet opening.

4. An apparatus of the character described having in combination, a substantially closed chamber having a flat bottom and an upper area of substantially semi-spherical contour, an elongated hollow member open at its lower end and closed

at its upper end and engaged vertically in liquid-tight relation through the upper portion of said chamber and having its open lower end in spaced relation to the bottom of said chamber, means for adjusting the vertical position of said hollow member, means for locking said member in adjusted position, an inlet opening adjacent the lower portion of said chamber, and a plurality of discharge orifices in the upper portion of said chamber, said orifices being collectively of less area than the area of the inlet opening.

5. An apparatus of the character described having in combination, a substantially closed chamber having a flat bottom and an upper area of substantially semi-spherical contour, an elongated hollow member open at its lower end and closed at its upper end and engaged in liquid-tight relation through the upper portion of said chamber and having its open lower end in spaced relation to the bottom of said chamber, an inlet conduit for liquid extending through the lower portion of said chamber and terminating in a vertical discharge nozzle positioned centrally beneath the lower open end of said hollow member, and a plurality of discharge orifices in the upper portion of said chamber, said orifices being collectively of less area than the area of the inlet opening.

6. An apparatus of the character described having in combination, a substantially closed chamber having a flat bottom and an upper area of substantially semi-spherical contour, an elongated hollow member open at its lower end and closed at its upper end and engaged vertically in liquid-tight relation through the upper portion of said chamber and having its open lower end in spaced relation to the bottom of said chamber, means for adjusting the vertical position of said hollow member, an inlet conduit for liquid extending through the lower portion of said chamber and terminating in a vertical discharge nozzle positioned centrally beneath the lower open end of said hollow member, and a plurality of discharge orifices in the upper portion of said chamber, said orifices being collectively of less area than the area of the inlet opening.

7. An apparatus of the character described having in combination, a substantially closed chamber having a flat bottom and an upper area of substantially semi-spherical contour, an elongated hollow member open at its lower end and closed at its upper end and engaged vertically in liquid-tight relation through the upper portion of said chamber and having its open lower end in spaced relation to the bottom of said chamber, means for adjusting the vertical position of said hollow member, means for locking said member in adjusted position, an inlet conduit for liquid extending through the lower portion of said chamber and terminating in a vertical discharge nozzle positioned centrally beneath the lower open end of said hollow member, and a plurality of discharge orifices in the upper portion of said chamber, said orifices being collectively of less area than the area of the inlet opening.

HENRY L. FRIEDMAN.
